PROPELLUTION OF BOATS

William Riseam, Hull, England, assignor of one-half to John Herbert Haiste, Hull, England

Application November 19, 1934, Serial No. 753,754
In Great Britain February 9, 1934

3 Claims. (Cl. 115—24)

This invention relates to the propulsion of boats and it has for its primary object to supply an improved means of propulsion in substitution for one or more sculls or oars, another object being to substitute for one or more sculls or oars improved boat propelling means adapted either for manual or mechanical operation, and a further object being to provide manual or mechanical boat propelling means occupying a minimum of space and hence especially suitable for use in conjunction with collapsible boats in which said propelling means may be accommodated when the boat is collapsed or folded.

Manually-operated and engine-operated oscillating propellers have already been proposed for the propulsion of boats, and it has also been proposed to employ an oscillating propeller whereof the blade or blades is or are mounted pivotally at right angles to a propeller shaft to which angular movement about its own longitudinal axis in opposite directions alternately is imparted by actuating means therefor, the blade or blades being caused by the pressure of water to swing about its axis or their axes at each change in direction of the angular movement of the propeller shaft.

According to this invention a rotary propeller has blades mounted pivotally at right angles in relation to a propeller shaft to which one or more revolutions in opposite directions alternately is or are imparted by actuating mechanism and the blades swing automatically under water pressure about their axes at each change of the direction of rotation of the propeller shaft whereby the thrust on the propeller blades is constantly effective.

The propeller shaft may be actuated either manually or mechanically through the medium of an internally threaded block or sleeve working as a nut on a threaded shaft aligned with and connected to said propeller shaft, which threaded sleeve is adapted to be reciprocated along said threaded shaft by a manually operated angularly movable lever connected by a link to said sleeve; the sleeve being prevented from rotating by engagement with a fixed rod on which the sleeve is slidable.

The propeller comprises a pair of diametrically opposite blades each mounted pivotally on a stem fixed to a boss and extending at right angles to a propeller shaft wherein the boss is fixed, means being provided to limit adjustably, the extent of pivotal movement of said blades, and to the propeller shaft angular movement of not less than 360°, is imparted in opposite

directions alternately through the medium of the aforesaid actuating means.

When the threaded block or sleeve is reciprocated manually or mechanically, the shaft and propeller make one or more complete revolutions (according to the pitch or the length of the threaded rod) in one direction and then the opposite and at each reversal of direction the pressure of the water on the faces of the blades automatically turns each blade on its pivot, thus maintaining the thrust on the propeller blades continuously in a forward direction.

One constructional embodiment of the invention is shown in the accompanying drawings, in which Figure 1 is a longitudinal section of a two-bladed propeller and the actuating means therefor, and Figure 2 is a section on the line 2—2 in Figure 1. Figure 3 is a plan view of a portion of the actuating means.

Figure 4 is a detail plan view of an abutment ring for controlling a propeller blade, and Figure 5 is a detail plan view of part of the means for reversing the blades of the propeller illustrated in Figure 1.

Figure 6 is a longitudinal section of a gear box and propeller-actuating means.

The propeller shaft 7 passes through the sternpost 8 of a boat into a casing 9 on to the shouldered and reduced outboard end 9A of which a nut 10 is screwed to hold that end of the casing firmly against the sternpost 8, and beyond said nut 10 a packing gland 11 is also screwed on to the outboard extremity 9A of the casing 9.

Within the casing 9 the propeller shaft 7 is supported in ball bearings 12, 12, immediately of which the shaft is formed with a quick-pitched screw thread 13 which is embraced by a sleeve 14 adapted to work thereon as a nut by means of oppositely located thrust rollers 15, 15, carried by stubs 16, 16, accommodated in recesses interiorly of the sleeve 14. The sleeve 14 may, if desired, be in the form of a solid bronze nut without said thrust rollers.

The casing 9 is shaped lengthwise with two diametrically opposite wings 9B, 9B, serving as guides or grooves for ball races 17, 17, carried by horizontally disposed trunnions 18, 18, projecting laterally from the sleeve 14, and to the sleeve 14 are connected a pair of rods 19, 19, which pass slidably through apertures in the end or cover plate 9C of the casing 9, the outer ends of said rods 19, 19, being united by a gudgeon pin 20 to which is articulated a yoke 21 con-

necting the rods 19, 19, pivotally to a hand lever 22, the foot of which is pivoted at 22A to a bracket 22B fixed within the boat. 14A, 14A, are cushioning springs located within the casing 9 and serving as resilient abutments for the sleeve 14 at each end of the casing which preferably contains a supply of oil.

The propeller shaft 7 is bored longitudinally and the propeller boss 23 is secured to the 10 tapered outboard extremity thereof by means of an annular tapered and flanged plate 24 bolted at 25, 25, to the boss 23 and a nut 26 screwed on to the end of shaft 7, the boss 23 being recessed at 27 to accommodate said nut 26, and 15 a screwed plug or cap 28 being fitted on to the outboard end of the boss 23. 29 is a post supporting the inboard end of the casing 9, and 30 is a forked bracket integral with the cover plate 9C.

31, 31, are the two propeller blades in the root of each of which is formed an axial passage whereby each blade is mounted loosely on a stem or pintle 32 (wherein it is retained by a washer and split pin or otherwise suitably) 25 these pintles 32 being integral with or fixed to an arbor 33 disposed vertically in bearings formed diametrically of the boss 23 and the intermediate portion of the arbor being formed as a pinion 34.

30 The root of each blade 31 is circular and fits rotatably into a ring 35 fast on each pintle 32, and the trailing edge of each blade 31 terminates at its root in a lug or projection 36 which is accommodated in a segmental gap or recess 37 formed in each ring 35.

The propeller boss 23 is bored longitudinally at 38 to accommodate a forked rack 39 to the forward end of which is secured a rod 40 passing slidably through the longitudinal bore of the propeller shaft 7 and terminating at its forward extremity in a thrust collar 41 in which the rod 40 is free to rotate and which is furnished with trunnions 42, 42, engaged by a forked lever 43 pivoted at 44 to the aforesaid bracket 30 and provided with a handle 45.

50 In the form of the invention shown the length of the screw thread 13 is calculated so that for one passage of the sleeve 14 therealong angular movement to the extent of five complete revolutions is imparted to the propeller shaft 7, consequently, by oscillating the hand lever 22 continuously the resultant reciprocation of the sleeve 14 causes the propeller blades 31, 31, to be rotated for five revolutions, first in one direction and then in the opposite, the blades swinging angularly about the stems or pintles 32, 32, at each change in rotational direction, and abutting against the one or the other side of the segmental gap or recess 37 in each ring 35, whereby the thrust of the blades 31, 31, is effective constantly in a forward direction irrespective of the direction of rotation of the shaft 7 and is also continuously effective through both the forward and the aft displacement of the sleeve 14 along the screw thread 13.

65 In Figure 1 the propeller is shown with the blades 31, 31, in position for propelling a boat forwardly, but should it be desired to go astern, the rod 40 is moved longitudinally through the medium of handle 45, lever 43 and thrust collar 41, causing the rack 39 to rotate the pinion 34, arbor 33 and rings 35, 35, fast thereon, whereby the trailing edges of each blade 31 are moved forward and the leading edges aft, thus reversing the propeller which then functions to

propel the boat astern when the hand lever 22 is oscillated with the blades set in such position.

The embodiment of the invention just described is applicable to relatively small and light boats, and should the invention be required for use in connection with boats of a heavier type, or wherein more manual power is available, such as in ships' lifeboats, fishing boats or cobles, the operating mechanism may be associated with a gear box, as illustrated by way of example in Figure 6.

The casing 46 of the gear box is formed integrally with a forwardly extending tubular housing 47 in which is mounted in ball bearings 48, 48, a screw-threaded shaft 49 whereof the 15 thread is of the same pitch and length as the thread 13 shown in Figure 1, and said shaft 49 is prolonged into the gear box wherein it is supported by a ball bearing 50 accommodated in an appropriate recess in the end or cover plate 51 of the gear box.

20 Mounted freely on the shaft 49 is a pinion 52 having on its outer face a number of dogs 53 forming part of a clutch adapted to be engaged by another series of dogs 54 integral with a 25 slidable pinion 55 which is splined on the shaft 49 and having a neck engaged by a clutch fork 56 on the end of a clutch lever 57 pivoted at 58 in the gear box.

20 The pinion 52 meshes with a pinion 59 keyed 30 on a counter-shaft 60 supported by ball bearings 61, 62, accommodated in recesses in the front wall of the gear box 46 and its cover plate 51, respectively, and a pinion 63 engageable with the slidable pinion 55 is also keyed on said 35 counter-shaft 60 whereof the after end 60A projects through the cover plate 51 and is adapted to be coupled appropriately to the propeller shaft or to have the propeller boss 23 coupled directly to it in a manner similar to that shown 40 in Figure 1; the counter-shaft 60 being bored axially to accommodate the reversing rod 40 whereof the forward end terminates rotatably in a thrust collar 64 engaged by a fork 65 borne 45 by a reversing lever 66 pivoted at 67 to the housing 47.

50 The screw-threaded shaft 49 is engaged by a sleeve similar to the sleeve 14 and the latter is adapted to be displaced or reciprocated along the shaft 49 by means similar or analogous to 55 those already described with reference to Figure 1.

With the pinions 55 and 63 in mesh, as shown in Figure 6, the actuating mechanism revolves the propeller in low gear, and by sliding the dogs 54 into engagement with the dogs 53, by 55 moving the change-speed lever 57 aft, or to the left in Figure 6, the drive is transferred to the pinions 52 and 59 whereof the gear ratio is higher than pinions 55 and 63.

65 While the invention has been designed primarily to provide an improved manually-operated boat-propulsion mechanism, in certain cases a mechanical drive for reciprocating the sleeve 14 may be employed, such as a pivoted connecting rod coupling the rods 19 with a crank-pin on the fly wheel of a small internal combustion engine.

70 What I claim is:

1. Means for the propulsion of a boat, comprising a propeller shaft, a propeller including blades mounted pivotally in relation to said propeller shaft, each of said blades having a leading edge and also a trailing edge, means to rotate said propeller shaft through an angle of at least 75

- 360° in opposite directions alternately, and mechanism for reversing the positions of said leading edges and said trailing edges of said blades for the purpose of propelling said boat 5 astern, the thrust on said blades being constantly effective during both directions of angular movement of said propeller shaft and both when said boat is being propelled ahead and astern.
2. Means for the propulsion of a boat, comprising a propeller shaft, a propeller including blades mounted on axes at right angles in relation to said propeller shaft, said blades having limited pivotal movement about said axes and each blade having a leading edge and a trailing edge, means to rotate said propeller shaft a plurality of revolutions in one direction and a plurality of revolutions in the opposite direction alternately, and mechanism for reversing the positions of said leading edges and said trailing edges of said blades for the purpose of propelling said boat astern, the thrust on said blades being constantly effective during both directions of angular movement of said propeller shaft and also both when said boat is being propelled ahead and astern.
3. Means for the propulsion of a boat, comprising a propeller shaft, a propeller including blades mounted on axes at right angles in relation to said propeller shaft, said blades having limited pivotal movement about said axes and each blade having a leading edge and a trailing edge, means such as a sleeve adapted to be reciprocated as a nut upon a screw-threaded portion of said propeller shaft to rotate said propeller shaft a plurality of revolutions in one direction and a plurality of revolutions in the opposite direction alternately, and means such as rack-and pinion mechanism for reversing the positions of said leading edges and said trailing edges of said blades for the purpose of propelling said boat astern, the thrust on said blades being constantly effective during both directions of angular movement of said propeller shaft and also both when said boat is being propelled ahead and astern.

WILLIAM RISEAM.
